(57) **ABSTRACT**

An active noise control device includes: a reference signal source that outputs a reference signal having a correlation with noise; a reference signal input unit configured to receive the reference signal output from the reference signal source; a compressor that compresses the reference signal and outputs a compressed signal of the reference signal when an amplitude of the reference signal received by the reference signal input unit is greater than or equal to a threshold; and an adaptive filter unit configured to generate a canceling signal having a phase opposite to a phase of the compressed signal by multiplying the compressed signal using an adaptive filter having a coefficient that is updated successively. The coefficient of the adaptive filter is updated using a step size parameter for determining an amount of updating the coefficient of the adaptive filter based on a change in the amplitude of the reference signal.

**ACTIVE NOISE CONTROL DEVICE,
VEHICLE, AND ACTIVE NOISE CONTROL
METHOD**

**CROSS REFERENCE TO RELATED
APPLICATION**

The present application claims the benefit of Japanese Patent Application No. 2018-194137 filed Oct. 15, 2018. The entire disclosure of the above-identified application, including the specification, drawings and claims is incorporated herein by reference in its entirety.

FIELD

The present disclosure relates to an active noise control device that actively reduces noise by producing interference between the noise and a canceling sound, a vehicle including the active noise control device, and an active noise control method.

BACKGROUND

Conventionally, an active noise control device has been known that actively reduces noise by emitting a canceling sound for canceling the noise from a canceling sound source using a reference signal having a correlation with the noise and an error signal based on a residual sound resulting from interference between the noise in a predetermined space and the canceling sound (for example, see Patent Literature (PTL) 1). The active noise control device generates a canceling signal for emitting the canceling sound using an adaptive filter in such a manner that the sum of squares of the error signal is minimized.

Patent Literature

[PTL 1] International publication No. 2014/006846

SUMMARY

Technical Problem

However, the active noise control device disclosed in PTL 1 can be improved upon. In view of this, the present disclosure provides an active noise control device, a vehicle, and an active noise control method capable of improving upon the above related art.

Solution to Problem

An active noise control device according to one aspect of the present disclosure includes: a reference signal source that outputs a reference signal having a correlation with noise; a reference signal input unit configured to receive the reference signal output from the reference signal source; a compressor that compresses the reference signal and outputs a compressed signal of the reference signal when an amplitude of the reference signal received by the reference signal input unit is greater than or equal to a threshold; and an adaptive filter unit configured to generate a canceling signal having a phase opposite to a phase of the compressed signal by multiplying the compressed signal using an adaptive filter having a coefficient that is updated successively. The coefficient of the adaptive filter is updated using a step size

2

parameter for determining an amount of updating the coefficient of the adaptive filter based on a change in the amplitude of the reference signal.

Advantageous Effects

The active noise control device, etc. according to one aspect of the present disclosure is capable of improving upon the above related art.

BRIEF DESCRIPTION OF DRAWINGS

These and other objects, advantages and features of the present disclosure will become apparent from the following description thereof taken in conjunction with the accompanying drawings that illustrate a specific embodiment of the present disclosure.

FIG. 1 is a schematic top view of a car including an active noise control device according to Embodiment 1.

FIG. 2 is a block diagram illustrating a functional configuration of the active noise control device according to Embodiment 1.

FIG. 3 is a flow chart of a basic operation of the active noise control device according to Embodiment 1.

FIG. 4 illustrates signal processing performed by a compressor when the amplitude of a reference signal is greater than or equal to a threshold.

FIG. 5 illustrates signal processing performed by the compressor when the amplitude of the reference signal is less than the threshold.

FIG. 6 is a flow chart of an operation for stopping updating of a coefficient of an adaptive filter when a compressed reference signal is being output from the compressor.

FIG. 7 is a block diagram illustrating a functional configuration of an active noise control device according to Embodiment 2.

FIG. 8 is a block diagram illustrating a functional configuration of an active noise control device according to a variation of Embodiment 2.

DESCRIPTION OF EMBODIMENTS

Hereinafter, embodiments are specifically described with reference to the drawings. Note that the embodiments described below each show a general or specific example. Numerical values, shapes, materials, structural components, arrangement and connection configuration of the structural components, steps, and the order of the steps shown in the following embodiment are mere examples, and are not intended to limit the present disclosure. Moreover, among the structural components in the following embodiments, structural components not recited in any of the independent claims defining the broadest concepts of the present disclosure are described as optional structural components.

Moreover, the respective figures are schematic illustrations and are not necessarily precise illustrations. Note that, in the figures, substantially identical structural components share like reference signs, and overlapping explanations may be omitted or simplified.

Embodiment 1

Configuration of Car Including Active Noise Control Device

Embodiment 1 describes an active noise control device provided in a car. FIG. 1 is a schematic top view of a car including an active noise control device according to Embodiment 1.

Car **50** is an example of a vehicle, and includes active noise control device **10** according to Embodiment 1, reference signal source **51**, canceling sound source **52**, error signal source **53**, and car body **54**. Specifically, car **50** is an automobile, but is not particularly limited to this.

Reference signal source **51** is a transducer that outputs a reference signal having a correlation with noise in space **55** of the passenger compartment of car **50**. In Embodiment 1, reference signal source **51** is an acceleration sensor, and is placed outside of space **55**. Specifically, reference signal source **51** is mounted on a sub frame near a left front wheel (or a wheel well of the left front wheel). Note that the position of mounting reference signal source **51** is not particularly limited to this. Furthermore, reference signal source **51** may be a microphone.

Canceling sound source **52** emits a canceling sound to space **55** using a canceling signal. In Embodiment 1, although canceling sound source **52** is a loudspeaker, a canceling sound may be emitted by exciting a component structure (for example, sun roof etc.) of car **50** using a drive mechanism, such as an actuator. Furthermore, in active noise control device **10**, a plurality of canceling sound sources **52** may be used, and the position of mounting canceling sound source **52** is not particularly limited.

Error signal source **53** detects a residual sound resulting from interference between the noise and the canceling sound in space **55**, and outputs an error signal based on the residual sound. Error signal source **53** is a transducer such as a microphone, and may be desirably placed in space **55**, such as on a headliner. Note that car **50** may include a plurality of error signal sources **53**.

Car body **54** is a structure formed by a chassis, a body, etc. of car **50**. Car body **54** forms space **55** (space in the passenger compartment) in which canceling sound source **52** and error signal source **53** are placed.

Configuration of Active Noise Control Device

Next, the configuration of active noise control device **10** will be described. FIG. 2 is a block diagram illustrating a functional configuration of active noise control device **10**.

As illustrated in FIG. 2, active noise control device **10** includes: reference signal input terminal **11**, canceling signal output terminal **12**, error signal input terminal **13**, compressor **14**, adaptive filter unit **15**, simulated acoustic transfer characteristic filter unit **16**, filter coefficient updater **17**, and storage **18**. Compressor **14**, adaptive filter unit **15**, simulated acoustic transfer characteristic filter unit **16**, and filter coefficient updater **17** may be implemented by, for example, executing software by a processor or a microcomputer such as a digital signal processor (DSP). Compressor **14**, adaptive filter unit **15**, simulated acoustic transfer characteristic filter unit **16**, and filter coefficient updater **17** each may be implemented as hardware, such as a circuit. Moreover, a part of compressor **14**, adaptive filter unit **15**, simulated acoustic transfer characteristic filter unit **16**, and filter coefficient updater **17** may be implemented as software, and the other parts of those structural components may be implemented as hardware.

Basic Operation

As described above, active noise control device **10** performs a noise reduction operation. First, a basic operation of active noise control device **10** will be described with reference to FIG. 3 as well as FIG. 2. FIG. 3 is a flow chart of the basic operation of active noise control device **10**.

First, the reference signal having a correlation with noise **N0** is input from reference signal source **51** to reference signal input terminal **11** (S11). Reference signal input terminal **11** is an exemplary reference signal input unit, and is particularly a terminal made of metal, etc.

The reference signal input to reference signal input terminal **11** is output to adaptive filter unit **15** and simulated acoustic transfer characteristic filter unit **16** via compressor **14**. In other words, compressor **14** is applied to the reference signal (S12). Compressor **14** performs signal processing of compressing the amplitude of the reference signal to suppress clipping of the reference signal (i.e., the peak portion of the reference signal is clipped and the waveform is changed) when the amplitude of the reference signal is greater than assumed. FIG. 4 illustrates signal processing performed by compressor **14**.

As illustrated in FIG. 4, compressor **14** compresses the amplitude of a reference signal input to reference signal input terminal **11** and having an amplitude greater than or equal to a threshold, and outputs the compressed reference signal. In other words, compressor **14** reduces the amplitude of a reference signal having an amplitude greater than or equal to a threshold to an amplitude corresponding to approximately the threshold, and outputs the resulting reference signal. The waveform of the reference signal remains substantially the same as the waveform of the reference signal that is not yet compressed. Moreover, as illustrated in FIG. 5, compressor **14** outputs, as it is, the reference signal input to reference signal input terminal **11** and having an amplitude less than the threshold.

Next, adaptive filter unit **15** generates a canceling signal by applying an adaptive filter to the reference signal output from compressor **14** (multiplying the reference signal output from compressor **14** using an adaptive filter) (S13). Adaptive filter unit **15** is implemented as a so-called finite impulse response (FIR) filter or infinite impulse response (IIR) filter. Adaptive filter unit **15** outputs the generated canceling signal to canceling signal output terminal **12**. The canceling signal is used to emit canceling sound **N1** for reducing noise **N0**, and is output to canceling signal output terminal **12** (S14).

Canceling signal output terminal **12** is an exemplary canceling signal output unit, and is a terminal made of metal, etc. Canceling signal output terminal **12** receives the canceling signal generated by adaptive filter unit **15**.

Canceling signal output terminal **12** is connected to canceling sound source **52**. Thus, canceling sound source **52** receives the canceling signal via canceling signal output terminal **12**. Canceling sound source **52** emits canceling sound **N1** based on the canceling signal.

Error signal source **53** detects a residual sound resulting from interference between noise **N0** and canceling sound **N1** emitted from canceling sound source **52** corresponding to the canceling signal, and outputs an error signal corresponding to the residual sound. Consequently, the error signal is input to error signal input terminal **13** (S15). Error signal input terminal **13** is an exemplary error signal input unit, and is a terminal made of metal, etc.

Next, simulated acoustic transfer characteristic filter unit **16** generates a filtered reference signal by correcting the reference signal using simulated transfer characteristics which simulate acoustic transfer characteristics from canceling signal output terminal **12** to error signal input terminal **13** (S16). In other words, simulated transfer characteristics simulate acoustic transfer characteristics from the position of canceling sound source **52** to the position of error signal source **53**. Simulated transfer characteristics are measured in space **55** in advance, and are stored on storage **18**,

for example. Note that simulated transfer characteristics may be defined by an algorithm which uses no predetermined value.

Storage **18** is a storage device that stores simulated transfer characteristics. Storage **18** also stores, for example, a coefficient of the adaptive filter, which will be described below. Specifically, storage **18** is implemented as a semiconductor memory, etc. Note that, when compressor **14**, adaptive filter unit **15**, simulated acoustic transfer characteristic filter unit **16**, and filter coefficient updater **17** each are implemented as a processor such as a DSP, storage **18** also stores a control program executed by the processor. Storage **18** may also store other parameters to be used for signal processing performed by compressor **14**, adaptive filter unit **15**, simulated acoustic transfer characteristic filter unit **16**, and filter coefficient updater **17**.

Filter coefficient updater **17** successively updates coefficient W of the adaptive filter based on the error signal and the generated filtered reference signal (S17).

Specifically, filter coefficient updater **17** uses the least mean square (LMS) method to calculate coefficient W of the adaptive filter in such a manner that the sum of squares of the error signal is minimized, and outputs the calculated coefficient of the adaptive filter to adaptive filter unit **15**. Furthermore, filter coefficient updater **17** successively updates the coefficient of the adaptive filter. Coefficient W of the adaptive filter is expressed as the following (Expression 1), where “ e ” denotes the vector of the error signal, “ R ” denotes the vector of the filtered reference signal. Note that n is a natural number and represents the n -th sample in sampling period T_s . Here, μ is a scalar quantity and is a step size parameter that determines an amount of updating coefficient W of the adaptive filter per sampling.

[Math. 1]

$$W(n+1) = W(n) - \mu \cdot e(n) \cdot R(n) \quad (\text{Expression 1})$$

Note that filter coefficient updater **17** may update coefficient W of the adaptive filter using a method other than the LMS method.

As described above, active noise control device **10** includes compressor **14**. Compressor **14** makes it possible to output a reference signal whose waveform is maintained to adaptive filter unit **15** and simulated acoustic transfer characteristic filter unit **16**, even when the amplitude of the reference signal is greater than assumed due to noise N_0 , etc. that has occurred unexpectedly. In other words, even when the amplitude of the reference signal is extremely large, a signal having substantially the same frequency components as those of the reference signal is output to adaptive filter unit **15** and simulated acoustic transfer characteristic filter unit **16**. Therefore, because an appropriate canceling signal is output from adaptive filter unit **15**, this prevents the canceling sound from being perceived as an abnormal sound.

Operation for Stopping Updating Coefficient of Adaptive Filter

In active noise control device **10**, when the amplitude of the reference signal is larger than assumed, the waveform of the reference signal may be clipped (i.e., the waveform of the reference signal may be changed). Consequently, noise cannot be reduced appropriately and the canceling sound may be perceived as an abnormal sound. When compressor **14** is compressing the reference signal (when the reference signal has an amplitude greater than or equal to the thresh-

old), even though noise N_0 is large, the reference signal is compressed to have a smaller amplitude and is output to adaptive filter unit **15** and simulated acoustic transfer characteristic filter unit **16**. Thus, the coefficient of the adaptive filter becomes large and the gain increases (i.e., the effectiveness of the adaptive filter becomes strong). If the compression ratio of compressor **14** decreases while the coefficient of the adaptive filter is large, even though noise N_0 is small, the effectiveness of the adaptive filter remains strong, and thus large canceling sound N_1 will be emitted and it may be perceived as an abnormal sound.

The amplitude of the reference signal being greater than or equal to the threshold is often caused when large noise N_0 is unexpectedly generated, and it is considered that such a state does not usually continue for a long time. Thus, filter coefficient updater **17** may stop updating the coefficient of the adaptive filter, when a compressed reference signal is being output from compressor **14**. FIG. 6 is a flow chart of such an operation for stopping updating the coefficient of the adaptive filter.

First, when filter coefficient updater **17** updates the coefficient of the adaptive filter (S21), information indicating the operating state of compressor **14** is obtained from compressor **14** (S22). The course of obtaining this information is illustrated with the dashed line arrow in FIG. 2. Next, filter coefficient updater **17** determines, based on the obtained information, whether compressor **14** is compressing the reference signal (S23). Note that filter coefficient updater **17** may monitor the amplitude of the reference signal input to reference signal input terminal **11**, and perform a similar determination as in Step S23 by comparing the amplitude with the threshold.

When filter coefficient updater **17** determines that compressor **14** is compressing the reference signal (Yes in S23), filter coefficient updater **17** stops updating the coefficient of the adaptive filter (S24). Specifically, filter coefficient updater **17** sets step size parameter $\mu=0$ in (Expression 1) above, and outputs the same coefficient of the adaptive filter to adaptive filter unit **15**. Stopping updating the coefficient of the adaptive filter can also be achieved by setting $W(n+1)=W(n)$ and not rewriting W . When filter coefficient updater **17** determines that compressor **14** is not compressing the reference signal (No in S23), filter coefficient updater **17** continues to update the coefficient of the adaptive filter.

As described above, filter coefficient updater **17** stops updating the coefficient of the adaptive filter when a compressed reference signal is being output from compressor **14**. This prevents large canceling sound N_1 from being emitted and being perceived as an abnormal sound, when the amplitude of the reference signal is returned to an amplitude less than the threshold.

Embodiment 2

Configuration of Active Noise Control Device According to Embodiment 2

The following describes a functional configuration of an active noise control device according to Embodiment 2. FIG. 7 is a block diagram illustrating the functional configuration of the active noise control device according to Embodiment 2. Note that, in following Embodiment 2, detailed description of the matters that have been already described will be omitted.

As illustrated in FIG. 7, car **150** is different from car **50** in that car **150** includes active noise control device **110** instead of active noise control device **10**. Active noise

control device **110** is different from active noise control device **10** in that active noise control device **110** includes μ adjuster **19**.

Here, μ adjuster **19** adjusts step size parameter μ in (Expression 1) above, and causes filter coefficient updater **17** to use step size parameter μ that has been adjusted. In other words, μ adjuster **19** instructs the value of step size parameter μ to the filter coefficient updater.

When the value of step size parameter μ is too large, the adaptive filter is more likely to diverge. When the value is too small, the coefficient of the adaptive filter of filter coefficient updater **17** is not be updated in time, and a noise reduction effect decreases. Accordingly, for example, μ controller **19** sets step size parameter μ to a smaller value as the amplitude of the reference signal becomes larger. Specifically, μ controller **19** sets step size parameter μ to a value proportional to the reciprocal of the average value of the amplitude of the reference signal in the latest predetermined period. At this time, step size parameter μ is not zero.

In such a case, when step size parameter μ is adjusted using the reference signal output from compressor **14**, the reference signal output from compressor **14** is compressed in some cases. In such cases, the value of step size parameter μ may not be adjusted appropriately.

In view of the above, in active noise control device **110**, μ adjuster **19** adjusts step size parameter μ using the reference signal that is not yet input to compressor **14** (i.e., reference signal which is input to reference signal input terminal **11**).

Such active noise control device **110** includes compressor **14**, and can also adjust step size parameter μ appropriately when the compressed reference signal is output from compressor **14**. Therefore, active noise control device **110** can improve the noise reduction effect when the compressed reference signal is output from compressor **14**.

Variation of Embodiment 2

Compressor **14** is implemented by performing software (control program) by a processor, such as a DSP, for example. When a user actually drives car **150** and sets a relationship between a threshold of compressor **14** and the amplitude of the reference signal, changing the design to amplify (or attenuate) the reference signal in a preceding stage and a following stage of compressor **14** may be easier than changing the threshold itself. Specifically, it is a case where a user wishes to implement compressor **14** by using existing software without any change. Accordingly, a gain adjuster may be placed in a preceding stage and a following stage of compressor **14**. FIG. 8 is a block diagram illustrating a functional configuration of an active noise control device according to a variation of Embodiment 2.

As illustrated in FIG. 8, car **250** is different from car **150** in that car **250** includes active noise control device **210** instead of active noise control device **110**. Active noise control device **210** is different from active noise control device **110** in that active noise control device **210** includes first gain adjuster **21**, second gain adjuster **22**, and third gain adjuster **23**.

First gain adjuster **21** multiplies the reference signal input to reference signal input terminal **11** by m , and outputs the multiplied reference signal to compressor **14**. Here, m is a positive number, and may be greater than or equal to 1, or less than 1. For example, first gain adjuster **21** may be implemented as hardware, such as an amplifier circuit, or may be implemented as software.

Second gain adjuster **22** multiplies the reference signal output from compressor **14** by n (n is a positive number), and outputs the multiplied reference signal to adaptive filter unit **15**. Here, n is a positive number, and may be greater than or equal to 1, or less than 1. For example, second gain adjuster **22** may be implemented as hardware, such as an amplifier circuit, or may be implemented as software.

With such first gain adjuster **21** and second gain adjuster **22**, the user can easily set the relationship between the threshold of compressor **14** and the amplitude of the reference signal.

With first gain adjuster **21** and second gain adjuster **22**, the reference signal is multiplied by $m \times n$ and output to adaptive filter unit **15**. At this time, active noise control device **210** includes third gain adjuster **23** so that μ adjuster **19** can appropriately adjust step size parameter μ .

Third gain adjuster **23** multiplies the reference signal that is not yet input to first gain adjuster **21** by $m \times n$, and outputs the multiplied reference signal. For example, third gain adjuster **23** may be implemented as hardware, such as an amplifier circuit, or may be implemented as software. Here, μ adjuster **19** adjusts step size parameter μ using the reference signal output from third gain adjuster **23**. Accordingly, μ adjuster **19** can appropriately adjust step size parameter μ .

Effects, Etc.

As described above, active noise control device **10** is an active noise control device that reduces noise N_0 in space **55** in car **50**. Active noise control device **10** includes: reference signal input terminal **11** that receives a reference signal output by reference signal source **51** mounted on car **50**, the reference signal having a correlation with noise N_0 ; compressor **14** that compresses the reference signal input to reference signal input terminal **11** and having an amplitude greater than or equal to a threshold, and outputs the reference signal compressed; adaptive filter unit **15** configured to generate a canceling signal to be used to output canceling sound N_1 for reducing noise N_0 by applying an adaptive filter to the reference signal output from compressor **14**; and filter coefficient updater **17** that updates a coefficient of the adaptive filter. Car **50** is an example of a vehicle and reference signal input terminal **11** is an exemplary reference signal input unit.

Because such active noise control device **10** includes compressor **14**, a reference signal whose waveform is maintained is output to adaptive filter unit **15**, even when the amplitude of the reference signal is greater than assumed due to noise N_0 , etc. that has occurred unexpectedly. In other words, a signal having substantially the same frequency components as those of the reference signal is output to adaptive filter unit **15**, even when the amplitude of the reference signal is extremely large. Therefore, active noise control device **10** can output a suitable canceling signal from adaptive filter unit **15**. Consequently, this prevents the canceling sound from being perceived as an abnormal sound.

Moreover, filter coefficient updater **17** stops updating the coefficient of the adaptive filter, when a compressed reference signal is being output from compressor **14**.

Such active noise control device **10** can prevent large canceling N_1 from being output and being perceived as an abnormal sound, when the reference signal is returned to an amplitude less than the threshold.

Moreover, in active noise control device **110**, filter coefficient updater **17** updates the coefficient of the adaptive filter using step size parameter μ . Active noise control device

110 further includes μ adjuster 19 that adjusts step size parameter μ using a reference signal that is not yet input to compressor 14.

Such active noise control device 110 includes compressor 14, and can also adjust step size parameter μ appropriately even when the compressed reference signal is being output from compressor 14. Thus, active noise control device 110 can improve the noise reduction effect when the compressed reference signal is being output from compressor 14.

Furthermore, active noise control device 210 further includes: first gain adjuster 21 that multiplies the reference signal received by reference signal input terminal 11 by m , where m is a positive number, and outputs the reference signal multiplied to compressor 14; second gain adjuster 22 that multiplies the reference signal output from compressor 14 by n , where n is a positive number, and outputs, to adaptive filter unit 15, the reference signal multiplied; and a third gain adjuster that multiplies the reference signal that is not yet input to first gain adjuster 21 by $m \times n$, and outputs, to μ adjuster 19, the reference signal multiplied. The μ adjuster 19 adjusts step size parameter μ using the reference signal output from third gain adjuster 23.

Such active noise control device 210 enables a user to easily set a relationship between the threshold of compressor 14 and the amplitude of the reference signal using first gain adjuster 21 and second gain adjuster 22. Furthermore, active noise control device 210 can appropriately adjust step size parameter μ .

Furthermore, each of active noise control devices 10, 110, and 210 further includes: canceling signal output terminal 12 that receives the canceling signal generated; error signal input terminal 13 that receives an error signal corresponding to a residual sound resulting from interference between canceling sound N1 and noise N0; and simulated acoustic transfer characteristic filter unit 16 that generates a filtered reference signal obtained by correcting the reference signal using simulated transfer characteristics that simulate acoustic transfer characteristics from canceling signal output terminal 12 to error signal input terminal 13. Filter coefficient updater 17 updates the coefficient of the adaptive filter using the error signal and the filtered reference signal. Canceling signal output terminal 12 is an exemplary canceling signal output unit, and error signal input terminal 13 is an exemplary error signal input unit.

Such active noise control devices 10, 110, and 210 can update the coefficient of the adaptive filter using the error signal and the filtered reference signal.

Furthermore, the active noise control method performed by a computer, such as active noise control device 10, is an active noise control method that reduces the noise in space 55 in car 50. Such an active noise control method includes: a first step of compressing a reference signal that is output from reference signal source 51 mounted on car 50, has a correlation with noise N0, and has an amplitude greater than or equal to a threshold, and outputting a compressed signal of the reference signal; a second step of generating a canceling signal that is used to emit canceling sound N1 for reducing noise N0 by applying an adaptive filter to the reference signal output in the first step; and a third step of updating the coefficient of the adaptive filter.

Similar to active noise control device 10, such an active noise control method can prevent the canceling sound from being perceived as an abnormal sound.

Other Embodiments

Hereinbefore, Embodiments 1 and 2 have been described, but the present disclosure is not limited to Embodiments 1 and 2 described above.

The active noise control device according to the above embodiments may be provided in a vehicle other than a car. The vehicle may be an aircraft or a ship, for example. The present disclosure may be achieved as a vehicle other than such a car.

Furthermore, the configuration of the active noise control device according to each of Embodiments 1 and 2 is an example. For example, the active noise control device may also include a structural component, such as a D/A converter, a filter, a power amplifier, or an A/D converter.

Furthermore, the processes performed by the active noise control device according to each of Embodiments 1 and 2 are examples. For example, a part of the processes described in the foregoing embodiment may be realized by analog signal processing instead of digital signal processing.

Furthermore, for example, in Embodiments 1 and 2, a process performed by a certain processing unit may be performed by a different processing unit. Furthermore, the order of a plurality of processes may be changed or the processes may be performed in parallel.

Furthermore, in Embodiments 1 and 2, each structural component may be realized by executing a software program suitable for each structural component. Each structural component may be realized by reading out and executing a software program recorded on a recording medium, such as a hard disk or a semiconductor memory, by a program executor, such as a CPU or a processor.

Furthermore, in Embodiments 1 and 2, each structural component may be realized by hardware. For example, each structural component may be a circuit (or an integrated circuit). The circuits may constitute a single circuit as a whole, or may be individual circuits. Furthermore, each of the circuits may be a general-purpose circuit, or may be a dedicated circuit.

Furthermore, each structural component may be a circuit (or an integrated circuit). The circuits may constitute a single circuit as a whole, or may be individual circuits. Furthermore, each of the circuits may be a general-purpose circuit, or may be a dedicated circuit.

Furthermore, an overall or specific aspect of the present disclosure may be implemented using a system, a device, a method, an integrated circuit, a computer program, or a computer-readable non-transitory recording medium such as a CD-ROM. Furthermore, an overall or specific aspect of the present disclosure may also be implemented by combining a system, a device, a method, an integrated circuit, a computer program, or a computer-readable non-transitory recording medium in any manner.

For example, the present disclosure may also be implemented as an active noise control method executed by the active noise control device (a computer or a DSP), or may also be implemented as a program for causing a computer or a DSP to execute the active noise control method. Furthermore, the present disclosure may be implemented as a vehicle (for example, a car) or a noise reduction system including the active noise control device according to the foregoing embodiments and a reference signal source.

The present disclosure includes, for example, embodiments that can be obtained by various modifications to the respective embodiments and variations that may be conceived by those skilled in the art, and embodiments obtained by combining structural components and functions in the respective embodiments in any manner without departing from the essence of the present disclosure.

INDUSTRIAL APPLICABILITY

The active noise control device according to the present disclosure is useful as an active noise control device capable of reducing noise in a passenger compartment, for example.

11

While various embodiments have been described herein above, it is to be appreciated that various changes in form and detail may be made without departing from the spirit and scope of the invention(s) presently or hereafter claimed.

Further Information about Technical Background to this Application

The disclosure of the following Japanese Patent Application including specification, drawings and claims is incorporated herein by reference in its entirety: Japanese Patent Application No. 2018-194137 filed Oct. 15, 2018.

The invention claimed is:

1. An active noise control device, comprising:
  - a reference signal source that outputs a reference signal having a correlation with noise;
  - a reference signal input configured to receive the reference signal output from the reference signal source;
  - a first gain adjuster that multiplies the reference signal received by the reference signal input by m , where m is a positive number, and outputs, to a compressor, the reference signal multiplied by m ;
  - the compressor that compresses an amplitude of the reference signal multiplied by m within a threshold so that clipping of the reference signal multiplied by m is suppressed and outputs a compressed signal of the reference signal multiplied by m when the amplitude of the reference signal multiplied by m is greater than or equal to the threshold;
  - a second gain adjuster that multiplies the compressed signal output from the compressor by n , where n is a positive number, and outputs, to an adaptive filter, the compressed signal multiplied by n ;
  - the adaptive filter configured to generate a canceling signal having a phase opposite to a phase of the compressed signal multiplied by n , the compressed signal multiplied by n being multiplied using the adaptive filter, the adaptive filter having a coefficient that is updated successively;
  - a filter coefficient updater that updates the coefficient of the adaptive filter using a step size parameter, the step size parameter determining an amount of updating the coefficient of the adaptive filter based on a change in the amplitude of the reference signal;
  - a third gain adjuster that multiplies the reference signal that is not yet input to the first gain adjuster by mxn , and outputs, to a μ adjuster, the reference signal multiplied by mxn ; and
  - the μ adjuster that adjusts the step size parameter using the reference signal multiplied by mxn and output from the third gain adjuster.
2. The active noise control device according to claim 1, wherein
  - updating the coefficient of the adaptive filter is stopped while the compressor outputs the compressed signal.
3. The active noise control device according to claim 1, further comprising:
  - a canceling signal output configured to receive the canceling signal;
  - an error signal input configured to receive an error signal that corresponds to a residual sound resulting from interference between the noise and a canceling sound for reducing the noise, the canceling sound being generated using the canceling signal output from the canceling signal output; and
  - a simulated acoustic transfer characteristic filter configured to generate a filtered reference signal obtained by

12

correcting the reference signal using simulated transfer characteristics that simulate acoustic transfer characteristics from the canceling signal output to the error signal input, wherein

- 5 the coefficient of the adaptive filter is further updated using the error signal and the filtered reference signal.
4. A vehicle, comprising:
  - the active noise control device according to claim 1.
5. The active noise control device according to claim 1, wherein a waveform of the compressed signal is same as a waveform of the reference signal.
6. The active noise control device according to claim 1, wherein the compressed signal and the reference signal have a same frequency.
7. The active noise control device according to claim 1, wherein the compressed signal and the reference signal have a same wavelength.
8. An active noise control method, comprising:
  - multiplying a reference signal by m , where m is a positive number, the reference signal being output from a reference signal source and having a correlation with noise;
  - compressing an amplitude of the reference signal multiplied by m within a threshold so that clipping of the reference signal multiplied by m is suppressed, the reference signal multiplied by m having the amplitude greater than or equal to the threshold;
  - outputting a compressed signal of the reference signal multiplied by m ;
  - multiplying the compressed signal by n , where n is a positive number;
  - generating a canceling signal having a phase opposite to a phase of the compressed signal multiplied by n by multiplying the compressed signal multiplied by n output in the multiplying using an adaptive filter, the adaptive filter having a coefficient that is updated successively;
  - updating the coefficient of the adaptive filter using a step size parameter, the step size parameter determining an amount of updating the coefficient of the adaptive filter based on a change in the amplitude of the reference signal;
  - multiplying the reference signal, that is not yet multiplied by m , by mxn , and
  - adjusting the step size parameter using the reference signal multiplied by mxn .
9. The active noise control method according to claim 8, wherein a waveform of the compressed signal is same as a waveform of the reference signal.
10. The active noise control method according to claim 8, wherein the compressed signal and the reference signal have a same frequency.
11. The active noise control method according to claim 8, wherein the compressed signal and the reference signal have a same wavelength.
12. An active noise control device, comprising:
  - a processor; and
  - a memory including a control program that, when executed by the processor, causes the processor to perform operations, the operations including:
    - receiving a reference signal output from a reference signal source, the reference signal having a correlation with noise;
    - multiplying the reference signal by m , where m is a positive number, the reference signal multiplied by m having an amplitude greater than or equal to a threshold;

13

compressing the amplitude of the reference signal multiplied by m within the threshold so that clipping of the reference signal multiplied by m is suppressed;
 outputting a compressed signal of the reference signal multiplied by m;
 multiplying the compressed signal by n, where n is a positive number;
 generating a canceling signal having a phase opposite to a phase of the compressed signal by multiplying the compressed signal multiplied by n using an adaptive filter, the adaptive filter having a coefficient that is updated successively;
 updating the coefficient of the adaptive filter using a step size parameter, the step size parameter determining an amount of updating the coefficient of the adaptive filter based on a change in the amplitude of the reference signal;
 multiplying the reference signal, that is not yet multiplied by m, by $m \times n$; and
 adjusting the step size parameter using the reference signal multiplied by $m \times n$.

13. The active noise control device according to claim 12, the operations further including:
 stopping the updating of the coefficient of the adaptive filter while the compressed signal is output.

14

14. The active noise control device according to claim 12, the operations further including:

receiving an error signal that corresponds to a residual sound resulting from interference between the noise and a canceling sound for reducing the noise, the canceling sound being generated using the canceling signal; and

generating a filtered reference signal obtained by correcting the reference signal using simulated transfer characteristics that simulate acoustic transfer characteristics from the canceling signal, wherein

the coefficient of the adaptive filter is further updated using the error signal and the filtered reference signal.

15. The active noise control device according to claim 12, wherein a waveform of the compressed signal is same as a waveform of the reference signal.

16. The active noise control device according to claim 12, wherein the compressed signal and the reference signal have a same frequency.

17. The active noise control device according to claim 12, wherein the compressed signal and the reference signal have a same wavelength.
